(57) **CLAIM**

The ornamental design for a shower adapter device, as shown and described.

DESCRIPTION

FIG. 1 is a top-front perspective view of the shower adapter device;

FIG. 2 is a bottom-front perspective view thereof;

FIG. 3 is a top view thereof;

FIG. 4 is a rear view thereof;

FIG. 5 is a right side view thereof;

FIG. 6 is a front view thereof;

FIG. 7 is a left side view thereof;

FIG. 8 is a bottom view thereof; and,

FIG. 9 is a cross-sectional view thereof taken along line 9-9 shown in FIG. 8.

The broken lines are included for the purpose of illustrating unclaimed features of the shower adapter device and form no part of the claimed design.

1 Claim, 9 Drawing Sheets
